UNITED STATES PATENT OFFICE.

JOSEPH PHILLIPS, OF CINCINNATI, OHIO, ASSIGNOR TO THE STERLING GLASS COMPANY, OF CINCINNATI, OHIO, A PARTNERSHIP.

DESIGN FOR A CUT-GLASS DISH.

SPECIFICATION forming part of Design No. 37,071, dated August 9, 1904.

Application filed November 11, 1903. Serial No. 180,782. Term of patent 7 years.

To all whom it may concern:

Be it known that I, JOSEPH PHILLIPS, a citizen of the United States of America, and a resident of Cincinnati, county of Hamilton, 5 State of Ohio, have invented a certain new, original, and ornamental Design for a Cut-Glass Dish, of which the following is a specification.

The figure is a plan view of a cut-glass dish, 10 showing my new design.

In the drawing the radiating non-intersect-

ing series of lines represent lines which in the dish are dull or unpolished, and the lines forming the figures represent lines which in the dish are polished.
